(57) **CLAIM**

The ornamental design for a cordless base for headset, as shown and described.

DESCRIPTION

FIG. 1 is a front, top, left perspective view of a cordless base for a headset showing our new design.

FIG. 2 is a rear elevational view of the cordless base for a headset.

FIG. 3 is a front elevational view of the cordless base for a headset.

FIG. 4 is a right elevational view of the cordless base for a headset.

FIG. 5 is a left elevational view of the cordless base for a headset

FIG. 6 is a top plan view of the cordless base for a headset; and,

FIG. 7 is a bottom plan view of the cordless base for a headset.

The broken lines are for illustrative purpose only and forms no part of the claimed design.
